UNITED STATES PATENT OFFICE.

GEORGE L. BENDER, OF SAN FRANCISCO, CALIFORNIA, ASSIGNOR OF ONE-HALF TO W. A. BENDER, OF SAN FRANCISCO, CALIFORNIA.

TIE-PLATING MACHINE.

SPECIFICATION forming part of Letters Patent No. 703,755, dated July 1, 1902.

Application filed October 26, 1901. Serial No. 79,895. (No model.)

To all whom it may concern:

Be it known that I, GEORGE L. BENDER, a citizen of the United States, residing in the city and county of San Francisco, State of California, have invented certain new and useful Improvements in Tie-Plating Machines; and I do hereby declare the following to be a full, clear, and exact description of the same.

The present invention relates to a certain new and useful apparatus for attaching the rail plates or chairs to railway-ties, which consists in means whereby the tie is centered to receive the plates or chairs in proper places and in controlled mechanism by means of which the said plates or chairs are gradually forced or driven into the ties.

In order to comprehend the invention, reference must be had to the accompanying sheets of drawings, wherein—

Figure 1 is a side view in elevation of the apparatus, partly broken away. Fig. 2 is a top plan view of the mechanism disclosed by Fig. 1 of the drawings with one of the cylinders removed. Fig. 3 is a cross-sectional view taken on line $\alpha\alpha$, Fig. 2 of the drawings, with tie in position. Fig. 4 is a similar view on line $v v$, Fig. 2, illustrating position of cylinder removed from said figure of the drawings and tie-plate in position within its gage-plate. Fig. 5 is a vertical sectional view of valve-cylinder and valve and connections which communicate with the piston-cylinders; Fig. 6, a perspective view of one of the tie-plates, and Fig. 7 a detail view of the die-plate attached to end of one of the pressure-pistons.

In the drawings, the numeral 1 is used to indicate any suitable form of frame which supports the rolls 2. To the ends of said frame are attached brackets 3 4, and to said brackets are fulcrumed the levers 5 6, which levers extend beyond the frame of the machine and are connected by rod 7. These levers at their inner ends have pivoted thereto the arms 8 9, which are attached, respectively, to longitudinal plates 10 11. Said plates rest upon the rolls 2 and act as centering means for the ties 12, fed therebetween. One end of the plates 11 12 is flared outwardly, as seen at 13, Fig. 2 of the drawings.

To one side of the bed-frame a short distance from each end I attach angle-plates 14

15. The upper face of each plate is cut away, so as to provide a socket a , corresponding in shape to the shape of the tie-plate 16, fitted therein, Fig. 2 of the drawings. These angle-plates or what I shall term "gage-plates" for the tie-plates are so arranged as to be a slight distance above the tie 12 when fitted within the machine. Said gage-plates 55 hold the tie-plates in proper position while being forced into the tie. Inasmuch as the tie-plates vary in size and shape, it is required that the gage-plates be detachably connected to the bed-frame, so that they may be readily 60 removed and ones attached having a tie-plate opening or seat which corresponds to the shape and size of the tie-plate to be used.

The tie-supporting rolls 2 work in bearings of brackets 17, bolted or otherwise secured to 70 the bed-frame. Each roll-bracket 17 rests upon a cushion 18², so that a slight give is permitted as pressure is exerted upon the supported tie to force the tie-plate 16 into the wood. The object of this give is to provide 75 against the rolls bruising or marring the under face of the tie when the same is forced downward by the pressure-pistons.

At the outer end of the bed-frame is fulcrumed the lever 18, the curved arm 19 of 80 which extends above the bed-frame 1 and serves as a stop for the inward movement of the tie 12.

Any suitable pressure means may be employed to force the tie-plates or chairs into 85 the wood of the ties. However, I prefer to use and have illustrated hydraulic means for this purpose. The hydraulic means consists of the piston-cylinders 20 21, supported by columns or standards 22, secured to the bed-frame 1, near each end thereof. Within these cylinders work the pistons 23, to the stem 24 of which is attached a head 25. The stem of the pistons works through a stuffing-box 26. An annular passage-way 27 exists 90 between the piston-stem and inner wall of the cylinders, with which connects a water-pipe 28. This pipe communicates with the water-supply pipe 29, which pipe connects with the valve-cylinder 30. Within this cylinder works the vertically-movable valve 31, the stem 32 of which is connected by link 33 to lever 34. This lever is fulcrumed to bracket 35, depending from cylinder 30. The body

portion of the valve is cut away, so as to leave an annular passage 36 between said body portion of the valve and the casing 37, fitted within the cylinder, and within which the 5 valve works. The water from supply-pipe 29 flows into this annular space through perforations 38 in the casing. The flow of water from the annular passage-way into outlet-pipe 39 is controlled by the movement of valve 31. 10 If the valve is raised, its collar 40 is carried off of its seat 41 and communication established between passage-way 36 and outlet-pipe 39. This pipe connects with the cylinders 20 and 21 above the piston 23. Consequently 15 the moment the valve 31 has been raised water under pressure enters the said cylinders and forces the pistons 23 downward. As thus moved downward the head 25 bears against the tie-plates 16 and forces the tongues or 20 projections 42 into the wood of the tie. The moment the water-pressure is cut off by the lever 34 being thrown to draw the valve 31 downward its full distance to seat the valve-collar 40 and close communication between 25 outlet-pipe 39 and passage-way 36 the pistons 23 are moved upward, so as to move head 25 off of tie-plate. This is due to the pressure of water admitted through pipe 28 into passage-way 27 being sufficient to force the pistons 30 tons 23 upward. Upon the return stroke of the pistons the water within the cylinders is forced back through outlet-pipe 39 into chamber 42' of cylinder 30 and is discharged therefrom through exhaust-pipe 43.

35 The pipe connections between the cylinders are preferably made in sections, thus permitting of same being shortened or lengthened. This adjustment is required in order that the piston-cylinders may be moved toward and from each other, so as to adjust the distance in accordance to the distance between the gage-plates for the tie-plates or chairs. Inasmuch as the gage of the railways is not uniform, the position of the gage- 40 plates must be changed in accordance with the gage of the road for the use of which the ties are plated. If a narrow-gage road, the tie-plates are attached closer together than in the case of a standard or broad gage. 45 The present machine is readily adapted for any gage required, it being only required that the gage-plates for the tie-plates be adjusted toward or from each other and that the position of the piston-cylinders be likewise altered, so that the piston-head will be in line with and bear upon the tie-plate held within the gage-plate. 50

Oftimes it is required that the tie-plate be not attached to the tie, but that the tie be 55 simply stamped to readily receive the tie-plate. For this purpose there is attached to the piston-heads a die 43', Fig. 7 of the drawings, which is provided with depending lugs 44 corresponding to those of the tie-plate. As 60 the pistons move downward these lugs are forced into the tie in the position that the tie-plate is to be fitted. When the pistons move

away from the tie, there will be left therein the impression of the tie-plate, the die being shaped to correspond with that of the tie-plate. As thus stamped the tie-plate may, when desired, be quickly and easily fitted within the impression thus made. 70

It will be understood that the described machine applies chairs as well as tie-plates 75 to the ties. To do this, it is only required that the piston-heads be changed in shape to accord with that of the chairs to be used.

By the use of the present machine the ties may be plated and kept on hand so plated until desired for use, or they may be shipped directly to the place desired as plated, thus saving much time in the work of constructing or repairing railway-work. If not desired to ship the ties plated, then the tie impressions may be made in the tie and the tie-plate properly placed when the tie is placed in the road-bed. 80 85

The advantage of plating the ties in this manner is that the work is done uniformly 90 and the tie-plates evenly attached to the ties.

The operation is as follows: A workman places a tie 12 between the centering plates 10 11 at their outwardly-flared end and moves same inward, the tie riding upon the supporting-rolls 2 until its inward movement or travel is stopped by end thereof contacting with arm 19 of fulcrumed lever 18. This lever is held downward by foot-pressure of the operator of the machine. When the tie 12 is thus placed within the machine, one of the levers 5 6 is thrown so as to draw the plates 10 11 together, causing same to firmly clasp the tie and center same to the vertical axis of the piston-heads 25. The moment the tie has been properly centered a tie-plate 16 is slipped or placed within socket or opening of each gage-plate 14 15, which gage-plates are so adjusted as to overlie the tie at points corresponding to the position for the tie-plates. As thus held within the gage-plates the lugs or projections 42 of the tie-plates 16 will rest upon the upper surface of the tie 12. Lever 34 is then moved so as to lift valve 31 in order to establish communication between the water-supply pipe and cylinders 20 and 21. The water-pressure thus admitted into the cylinders above the pistons 23 forces the pistons downward. As moved downward under high pressure the piston-stem heads 25 bear upon tie-plates 16 and force the lugs or projections 41 of same into the wood of the ties. Lever 34 is then thrown downward, so as to cause valve 31 to close the waterway. The pressure of water admitted through pipe 28 to cylinders 20 and 21 below the pistons 23 is sufficient to overcome the load of water resting thereon and to raise the pistons within the cylinders. As thus raised the water resting thereon is expelled from within the cylinders and forced back into cylinder 30, from which it escapes through exhaust-pipe. During the upstroke of the pistons the heads 25 are moved away from the tie-plates. 115 120 125 130

The tie as thus plated is then forced or moved through the machine and discharged therefrom from the end opposite to its entrance. To permit of this movement, the centering-
 5 plates 10 11 are moved away from the tie and the lever 18 released, when the tie is free to be moved through the machine. It will be understood that the operation is the same as that described in case the tie-plates are not used, but only a tie-plate impression be formed. Lever 18 is fulcrumed to a plate 18', adjustably attached to the bed-frame. By permitting of an adjustment at this point the position of the tie is regulated in accordance
 10 with the distance of the tie-plate from the end thereof. This adjustment of the lever overcomes the necessity as to adjusting or changing the position of cylinders 20 and gage-plate located therebelow, thus only requiring that cylinder 21 and its gage-plate be adjusted to obtain the desired distance between the tie-plates. After the parts have been once adjusted it is unnecessary to mark or measure each tie as to the position for securing the tie-plates, for after such adjustment the tie-plates will be attached to the ties uniformly, each tie receiving its tie-plates or tie-plate impression at the same point in accordance with the tie-gage required.
 15 30 While I have illustrated the parts as detachably secured to the bed-frame by bolts, it will be understood that any well-known means for adjustably connecting same to the bed-frame may be utilized.
 35 Having thus described the invention, what I claim as new, and desire to secure protection in by Letters Patent, is—

1. A tie-plating apparatus comprising means for receiving and centering a tie, devices for holding tie-plates gaged to the tie, and means for exerting pressure upon the tie-plates and driving same into the tie.
 40 2. A tie-plating apparatus comprising means whereby the tie is received and centered, spaced devices for receiving the tie-plates and holding same gaged to the tie, devices for limiting the inward movement of the tie and means for forcing the tie-plates into the tie.
 45 3. A tie-plating machine comprising means for receiving the tie to be plated, adjustable gage-plates for the tie-plates, mechanism whereby the tie is centered and held during the operation of plating, and adjustable means for exerting pressure upon the tie-plates and forcing same into the tie.
 50 4. In a tie-plating machine, the combination with the supporting-rolls for the tie, of means for centering and locking the tie to be plated.

5. In a tie-plating machine, the combination with the bed, of means for centering the tie placed thereon and holding same locked during the operation of applying tie-plates to the tie, gage-plates for the tie-plates, vertically-movable pistons for forcing the tie-plates into

the tie, and of means for imparting vertical movement to the said pistons.

6. In a machine of the described character, the combination with the bed, of tie-rolls arranged above the bed, cushions interposed between the bed and rolls, and means whereby the tie is centered and held centered. 70

7. In a tie-plating machine, the combination with the bed, of gage-plates for the tie-plates adjustably secured thereto, of means whereby the tie is centered and held centered during the operation of applying tie-plates to the tie, and mechanism whereby the tie-plates are forced into the tie. 75

8. In a machine of the described character, the combination with the bed, of the gage-plates attached thereto, means for centering and holding the tie centered to the work, of vertically-movable pistons, and mechanism 85 for imparting movement to said pistons.

9. The combination with the bed, of the gage-plates attached thereto, a lever for limiting the inward movement of the tie, said lever being adjustably attached to the bed, 90 and means for centering the tie and holding same centered to the work.

10. In a machine of the described character, the combination with the bed, of means for centering and holding the tie centered to the work, of the vertically-movable pistons, a die-plate attached to the stems thereof, and means for imparting movement to said pistons to force the dies carried thereby into the tie whereby an impression of the tie-plate is 95 formed in the tie at proper points.

11. In a machine for applying tie-plates to a railroad-tie, the combination with movable pressure devices located at a predetermined distance apart, of tie-supporter toward which 105 said movable pressure devices approach, and means for actuating said movable devices whereby the interposed tie-plates and tie are subjected to compression at the points of engagement between the tie-plates and tie. 110

12. In a machine for applying tie-plates to ties, the combination with movable pressure devices located at a predetermined distance apart, of tie-supporter toward which said movable pressure devices approach, and 115 means for actuating said movable pressure devices whereby the interposed tie-plates and tie are subjected to compression, and means adapted to engage one end of the tie to properly position the same with respect to the tie-plates. 120

13. In a machine for applying tie-plates to a railroad-tie, the combination with movable pressure devices located at a predetermined distance apart, of tie-supporter toward which 125 said movable pressure devices approach whereby the interposed tie-plates and tie are subjected to compression, and means for retaining the tie in proper position with respect to the tie-plates while the latter are being inserted.

14. In a machine for applying tie-plates to

a railroad-tie, the combination with movable pressure devices adjustably located at a pre-determined distance apart, of tie-supporter toward which said movable pressure devices approach, means for actuating said movable pressure devices whereby the interposed tie-plates and tie are subjected to compression, means adapted to engage an end of the tie to properly position the same with respect to the tie-plates, and means for retaining the tie in the desired position relative to the plates while the latter are being applied.

15. In a machine for applying tie-plates to a railroad-tie, the combination with cylinders

located at a predetermined distance apart, of pistons therein, of tie-supporter toward which such pistons are adapted to move and means for controlling the admission of fluid-pressure to said cylinders whereby the interposed tie-plates and tie are subjected to compression at the points of engagement between said plates and tie. 20

In witness whereof I have hereunto set my hand.

GEORGE L. BENDER.
